UNITED STATES PATENT OFFICE.

EDWARD E. WAKEFIELD, OF PROVIDENCE, RHODE ISLAND, ASSIGNOR TO HALKYARD MANUFACTURING COMPANY, OF PROVIDENCE, RHODE ISLAND, A CORPORATION OF RHODE ISLAND.

LACING-STUD-SETTING MACHINE.

1,129,030.

Specification of Letters Patent. Patented Feb. 16, 1915.

Application filed June 18, 1914. Serial No. 845,939.

To all whom it may concern:

Be it known that I, EDWARD E. WAKEFIELD, a citizen of the United States, and resident of the city of Providence, in the county of Providence and State of Rhode Island, have invented certain new and useful Improvements in Lacing-Stud-Setting Machines, of which the following is a specification.

10 This invention relates to improvements in machines for automatically setting lacing studs such as hooks or eyelets in shoe uppers, and has for its object to provide means adapted to work in conjunction with such a 15 machine for feeding a strip of reinforcing tape to the shoe upper to be connected to the upper by the setting of the lacing studs thereinto, this tape to serve as a support, reinforcement or backing for the thin upper 20 about the stud to prevent the latter from pulling out.

A further object of the invention is to provide means in the work feeding means for engaging and feeding or advancing the 25 tape in unison with the upper.

A further object of the invention is to provide means for severing the tape into predetermined lengths or into a length for each individual stud if desired, whereby the 30 tape is caused to readily take the natural form of the upper, and lie flat thereon without wrinkling or buckling.

With these and other objects in view, the invention consists of certain novel features 35 of construction, as will be more fully described and particularly pointed out in the appended claims.

In the accompanying drawings: Figure 1— is a front elevation of the usual lacing 40 hook setting machine to which my reinforcing tape feeding means is attached. Fig. 2— is an elevation of the machine partly in section showing the mechanism which controls the operation of the work feeding head. 45 Fig. 3— is a side elevation of a portion of the cam actuated mechanism for operating the work feeding head. Fig. 4— is a side elevation of the work feeding head showing the rods in section on which the head slides. 50 Fig. 5— is a perspective view showing a portion of the work feeding head carrying the needles or spurs which engage and advance the reinforcing strip with the work, also showing the knife which severs the

tape at the required intervals. Fig. 6— is a 55 side elevation showing the presser foot and the rod through which the same is manually raised to admit the work, also showing the aperture in the guide block above the presser foot through which the reinforcing tape is 60 fed. Fig. 7— is a front elevation of the feeding head partly in section showing the presser foot in engagement with the work, the reinforcing tape as having been fed into position to be severed and then carried down 65 onto the work by the punch which forms a hole to receive the lacing stud when advanced into the next position. Fig. 8— is a view of the feeding head partly in section showing the knife as having severed the reinforcing 70 strip and the punch as having passed therethrough and through the shoe upper. Fig. 9— is a view showing the feeding head as having advanced the work including the severed portion of reinforcing 75 tape into position to receive the lacing stud and said lacing stud as having been set therein, and the punch, cutter and feeding spurs as having been withdrawn and ready 80 to be carried to the right back into the position illustrated in Fig. 7 for the purpose of repeating the feeding operation. Fig. 10— is a plan of the presser foot showing the guide block slidably mounted thereon. Fig. 11— is a view of the inner side portion 85 of the shoe upper showing the tape as having been positioned to serve as a backing or reinforcement for the studs when riveted thereto. Fig. 12— is a greatly enlarged edge view of the work showing the lacing 90 studs in the form of hooks and eyelets as set into a shoe upper and my reinforcing tape in position to serve as a support or backing for the studs riveted in position in the work.

In the accompanying drawings I have 95 illustrated a hook setting machine with my tape feeding mechanism operatively connected thereto, but the same is as well adapted for use on an eyelet setting machine, as the tape serves as a reinforcement for either a hook or eyelet, and I have, therefore, adopted the term of lacing stud, which is used throughout the specification and claims and is intended to include both 100 the hook and the eyelet.

In these drawings 10 designates the base portion of the machine and 11 the frame

on which the feeding head 12 is mounted to slide transversely of the machine on the rods 13 and 14. This head receives its feeding motion, or stroke from the cam 15 through the rod 16, which is pivotally connected at 17 to the laterally extending slotted arm 18. This arm is secured to the sleeve 19, see Fig. 3, which is rotatably mounted on the shaft 20 and is provided near its forward end with a downwardly extending arm 21 having a slotted face 22 in which is mounted a slidably block 23, which block has a hole in its face to receive the pin 24 connected to the work feeding head or carriage 12, by which construction it will be seen that as the cam 15 rotates, the arm 18 is raised and lowered and through the sleeve 19 this head receives a lateral sliding movement on the guide rods 13 and 14 to feed the work. In order to control the extent of motion of this carriage on its guide rods, I have provided means for varying the spacing, which is that of moving the pivot pin 17 in the slotted arm 18 by the movement of the hand lever 25, which operates through the segments 26 and 27, bell crank 28, connector 29 to adjust the pivot point 17 and move the same either toward or from the center shaft 20 and so regulate the extent of movement.

In order to provide a vertically reciprocating motion of the stud setting spindle, I employ the cam 31 mounted on the shaft 32 which engages the lever 33 pivoted at 34; the upper end of said lever is provided with teeth 35 which engage those of the segmental gear 36 fixed to the shaft 20 by a set screw 37. On the opposite or front end of this shaft 20 is a crank pin 38 having a block 39 adapted to slide in the groove 40 in the longitudinally disposed member 41 secured to the spindle 30, whereby a rotating motion of the cam 31 oscillates the lever 33, which through the mechanism above described imparts a vertically reciprocated motion to the spindle 30. To this spindle is connected the punch 64 which forms a hole in the tape for the reception of the lacing stud, also on this spindle is mounted the cutter 62 for severing the reinforcing tape and a guide block 61 is connected to the spindle 30 for carrying one or more needles or spurs 60, which are arranged to engage the tape for the purpose of causing it to advance with the feeding movement of the head. The reinforcing tape "a" employed is preferably of a width a little greater than the turned over, riveted or spread portion of the end of the stud when riveted into position on the upper, and it may be constructed of any suitable material having strength or substance enough to properly support the stud when positioned in the upper. I preferably mount this tape on a reel 48 which is supported on a pin 49 in the

arm 50 connected in any suitable manner to the machine. The tape is led from the reel and threaded through a suitable guide 51. In this guide I have shown a tension spring 52 which may be adjusted by the nut 53 to regulate the pressure of the spring upon the tape to prevent the latter from moving backward when the feeding head returns after its forward feeding stroke. From this tube 51 the tape is led through the guiding aperture or slot 54 in the guide block 55 above the engaging surface of the presser foot 56. This block 55 is connected to the spring pressed spindle 57 and is shown as resting upon and adapted to slide in grooves 58 in the presser foot 56. This block is provided with apertures 59 through which the tape engaging needles or spurs 60 pass when forced into the tape for the purpose of feeding the same. These needles or spurs are supported in the bar 61 which is connected to the spindle 30 to move therewith. A knife 62 is also supported on this spindle 30 and extends downwardly to engage the front face of this block 55 so that when the spindle 30 descends the knife will engage and sever the portion 63 of the tape which extends through the block 55. The downward movement of this spindle 30 also causes the punch 64 to engage and carry the severed portion of the tape down against the shoe upper or work "b" and to punch a hole through the tape and also through the work to receive the stud as hereinafter described. The next motion after the punch has been inserted through the tape and work, is to raise the presser foot slightly, by means not shown, and at the same time to cause the feeding head to move to the left by mechanism above described. The work is next advanced bringing the punched hole in position to receive the stud "c" held in the pocket plate 65, see Fig. 8, which stud is ready to be raised in said plate by means (not shown) to be positioned and riveted in the punched hole by the anvil or spreading portion of the punch. After the stud has been set the spindle 30 is raised into position, see Fig. 9, removing the spurs and knife plate from engagement with the tape and the head is then carried to the right back into position shown in Fig. 7, which cycle of operations is repeated in the setting of each stud into the work.

In the operation of the machine it is desirable that the upper should receive a step by step movement to insure the proper spacing of the pieces of reinforcing material and the studs, and further to cause them to be applied to the upper near the outer edge thereof and conforming to the contour of said edge. To secure these results I provide a guiding gage 66 against which the outer edge of the upper is held as said upper is fed forward by the mechanism 125

heretofore described. In this manner the upper is turned slightly after each stud and its reinforcing material is applied thereto, so that the next stud and reinforcing material will be properly spaced with respect to said edge and to the previously applied stud.

In the constructing of shoes, the uppers are preferably made of very thin leather and therefore, require a backing or reinforcement about the lacing stud to prevent them from being drawn or pulled out, when a strain is applied to the same in lacing up the shoe, reinforcing strips of this character have heretofore been cut by a separate hand operation to conform to the shape or contour of the outer edge of the upper and must be positioned by hand of the operator and fed at the time of feeding the work to the machine. This operation of cutting the strips and feeding them to the machine by hand requires extra time and adds considerable to the cost of constructing the shoe upper. To obviate this difficulty I have provided a comparatively narrow tape, but of a sufficient width to form a suitable reinforcement for the lacing studs, and I feed this strip of tape automatically from the reel to the shoe upper, preferably by the mechanism that feeds the upper, and in order to prevent this tape from buckling or wrinkling which would be the case if caused to bend edgewise to take the shape of the curve about the edge of the upper, I simply sever the tape, or cut from the ribbon a separate piece for each stud, whereby these short pieces serve as reinforcing pads and each pad is automatically secured in position by the setting of its stud. By the use of my improved reinforcing tape and the mechanism for feeding the same, the work of preparing the strip by cutting it to shape is entirely eliminated, the work of positioning and feeding by hand is also eliminated and the total cost of preparing and positioning the reinforcing member is reduced to the minimum.

I have shown and described one form of mechanism for feeding, severing and connecting a ribbon or tape to the shoe upper, but any other suitable means may be employed for this purpose without departing from the spirit or scope of my invention.

I claim:

1. In mechanism for applying lacing studs to shoe uppers, means for feeding an upper, means for feeding a reinforcing strip a distance substantially equal to the feeding movement of the upper, and means for applying studs and severed sections of said reinforcing strip to said upper.

2. In mechanism for applying lacing studs to shoe uppers, means for feeding an upper, said feeding means including means for feeding a strip of reinforcing material a distance substantially equal to the feed-

ing movement of said upper, and means for applying studs and sections of said strip to said upper.

3. In mechanism for applying lacing studs to shoe uppers, means for imparting a feeding movement to the upper, means for simultaneously feeding a reinforcing strip a distance substantially equal to the said feeding movement of the upper, means for cutting said strip into sections, and means for attaching the studs and said sections to the upper.

4. In mechanism for applying studs to shoe uppers, means for imparting a step by step feeding movement to the upper, means for feeding a reinforcing strip a distance equal to the travel of each movement of said upper, means for securing studs to said upper and said strip, and means for cutting the strip before each stud is applied.

5. In mechanism for applying studs to shoe uppers, feeding mechanism for imparting a step by step movement to said upper, said feeding mechanism including means for feeding a reinforcing strip a distance substantially equal to the travel of each movement of said upper, and means for securing studs to said upper and to severed sections of said strip.

6. In mechanism for applying lacing studs to shoe uppers, the combination with means for feeding a strip of reinforcing material, means for securing lacing studs to severed sections of said strip and the shoe upper, and means for causing the studs and reinforcing material to be applied to the upper in a line conforming to the contour of the outer edge thereof.

7. In mechanism for applying lacing studs to shoe uppers, the combination with means for feeding a strip of reinforcing material, means for securing lacing studs to severed sections of said strip and the shoe upper, means for imparting a step by step movement to the upper, said strip and upper being fed substantially equal distances and a gage against which the outer edge of the upper is held by said movement imparting means, the construction and arrangement being such that the studs and reinforcing material are applied to the upper in a line conforming to the outer edge thereof.

8. In a machine of the class described, the combination with means for setting lacing studs, of means for feeding a strip of reinforcing tape to the shoe upper, means for imparting a feeding movement to the shoe upper substantially equal to the feeding movement of the tape, and means for cutting the strip before the severed section is secured in position to said upper.

9. In a lacing stud setting machine the combination with means for setting the studs, of means for feeding the work, means

in said work feeding means for advancing a strip of reinforcing tape a distance substantially equal to the feeding movement of the work, and means for cutting a length 5 from the strip and securing the same in position to said upper by the setting of the studs therein.

10. In a lacing stud setting machine the combination with means for setting said 10 studs, of means for feeding the work, and means in said work feeding means for advancing a strip of reinforcing tape a distance substantially equal to the feeding movement of the work to be secured to the 15 work by the setting of the studs therein.

11. In a lacing stud setting machine the combination with means for setting the studs, of means for feeding the work, and means in said work feeding means for advancing a strip of reinforcing tape a distance substantially equal to the feeding movement of the work to be secured to the work by the setting of the studs therein and means for regulating the length of a feeding 20 stroke for both the tape and upper.

25 12. In a lacing stud setting machine the

combination with means for setting the stud, of means for feeding the work, means in said work feeding means for advancing a strip of reinforcing tape with the work to be connected thereto by the stud when set therein; means for severing a predetermined length of tape from the strip before securing it to the upper and a tension device for retaining the tape during the return movement of the feeding mechanism.

30 35 13. In a lacing stud setting machine the combination with means for setting the studs in the work, of means for feeding the work, one or more spurs in said feeding 40 means for engaging and advancing a strip of reinforcing tape in unison with the work, said tape to support the upper about the stud when set therein, and means for severing the tape as the same is applied to the 45 upper.

In testimony whereof I affix my signature in presence of two witnesses.

EDWARD E. WAKEFIELD.
